UNITED STATES PATENT OFFICE.

WALTER E. FULLER, OF ROANOKE, VIRGINIA.

ASH-SIFTING DEVICE.

Application filed February 6, 1926. Serial No. 86,632.

This invention relates to attachment for furnaces, stoves or the like, and has for its object the provision of a novel device adapted to be mounted at the bottom of the ash-pit of a furnace and acting to sift the ashes and conduct away the dust so that only clean cinders will be left which may be shoveled out of the ashpit for subsequent use.

An important object is to provide a device of this character embodying motor operated suction means for withdrawing the dust, the motor of the suction producing mechanism also acting to effect vibration of a sifting screen so that the device will function properly and rapidly.

Yet another object is to provide a device of this character which may be installed beneath a furnace with comparatively small cost and in an easy manner, which will be simple to operate, positive in action, efficient and durable in service, and a general improvement in the art.

With the above and other objects and advantages in view, the invention consists in the details of construction and the arrangement and combination of parts to be hereinafter more fully described and claimed, and illustrated in the accompanying drawings, in which:-

Figure 1 is a front elevation of a furnace, partly in section, showing the invention applied thereto and showing the outlet therefrom leading into a flue or the like.

Figure 2 is a horizontal section through the ashpit showing a plan view of the device.

Figure 3 is a horizontal section taken on the line 3—3 of Figure 1.

Figure 4 is a detail end elevation of the suction producing device and agitating means for the screen.

Figure 5 is a detail view of the connection between the motor operated arm and the link member connected with the shaker or screen, and

Figure 6 is a detail perspective view of a link element forming part of the construction.

Referring more particularly to the drawings, the letter A designates a furnace having the usual ashpit B beneath which is located the present device.

In carrying out the invention I provide a casing or receptacle 10 mounted within a recess 11 in the cellar floor beneath the ash-pit B, the receptacle 10 being of partially spherical shape and provided at one side

with a relatively small conduit 12 which extends upwardly slightly beyond the cellar floor. Embedded or otherwise suitably mounted in the floor immediately beneath the ashpit is a ring member 13 having a depending inwardly extending flange 14 located within the receptacle 10. At the center of the bottom of the receptacle is a thickened portion 15 which constitutes a bearing for a vertical shaft 16 which has its upper end rotatably supporting a boss or socket member 17 formed on the underside of a screen member 18 which is circular in shape and which includes a plurality of radial arms 19 carrying a sheet or disk 20 of suitable wire screen of proper mesh.

It is of course intended that the screen 18 be rotatable and to limit the movement thereof in both directions, it is provided at 75 its underside with a depending projection 21 operating between a pair of spaced lugs 22 formed upon or carried by the receptacle 10. The rotatable screen member is also provided with an upstanding arm 23 formed with a socket member 24 for a purpose to be described.

Located upon the basement floor at some convenient point, preferably near the furnace, is a motor driven fan 25 not illustrated 85 in particular detail but of course including an electric motor and a suitable fan blade mechanism operating within a casing 26. Leading from this casing is an outlet pipe 27 with which connects a flexible conduit 28 90 terminating in a nozzle member or pipe 29 leading through the wall into the flue or simply out doors as may be preferred. Connected with the conduit 12 is an inlet pipe 30 which leads into the center of the fan casing 95 25 as clearly indicated.

The motor shaft 31 carries a disk 32 on which is mounted an eccentric pin 33 engaged within an elongated slot 34 in one arm of an angle lever 35 pivoted at 36 upon the frame of the suction or fan device. This angle lever further includes an arm 37 with which is pivotally connected, at 38, a link 39 carrying a ball head 40 engaged within the socket member 24. The link 39 extends 105 through a suitable opening 41 in the ash pit of the furnace as clearly indicated in Figure 1.

In the operation of the device, it will be readily apparent that ashes falling through 110 the grate B of the furnace will accumulate upon the screen 18. Whenever it is desired

to sift the ashes, it is clearly necessary that current be applied to the electric motor of the fan device so that the fan will be put in operation. Quite naturally, this fan will act to produce suction through the conduit 12 and within the receptacle 10 beneath the screen 18. At the same time, the rotation of the motor shaft will cause the angle lever 35 to be moved so that the link 39 will be correspondingly moved into a lengthwise direction so as to impart an oscillatory movement to the screen 18. Quite naturally, when the ashes fall upon the screen the movement thereof will cause the dust and fine matter to pass through into the receptacle 10 from which the dust and the like will be withdrawn through the conduit 12 and fan device and discharged through the conduit 28 and pipe or nozzle member 29 either out doors or into the flue, as the case may be. Obviously, the sifting of ashes will be thus accomplished in a very simple manner and after a few moments operation it is clear that only clean cinders will remain in the ash pit above the screen device, it being readily possible to remove or shovel out the cinders for subsequent use. It is really believed that the construction, operation and advantages will be readily apparent to one skilled in the art without further explanation.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:

1. In combination with the ash pit of a furnace, a receptacle mounted in the floor therebelow, and having a discharge conduit

from the bottom thereof, a ring-like bearing member located above and leading into the receptacle, a screen rotatably mounted upon said bearing member, a suction fan device connected with said outlet and having a discharge pipe, and crank means driven by the suction fan device and operatively connected with the screen for oscillating the latter.

2. In combination with the ash pit of a furnace, a receptacle located in the floor therebelow, a discharge conduit leading from the receptacle, a screen rotatably mounted above the receptacle, means for supporting the screen, means for limiting oscillatory movement of the screen, a suction fan device connected with said discharge conduit, and mechanical means operatively connected with the fan device and with the screen for oscillating the latter, said means comprising a pivoted angle lever having one arm provided with a link connection to the screen, and an eccentric pin carried by the fan shaft and engaging the other arm of the angle lever for moving the same.

3. A device of the character described, a receptacle located in the floor beneath the ash pit of a furnace and having a discharge conduit, a bearing member located above the receptacle, a supporting shaft rising centrally from the receptacle, a screen device rotatably mounted upon the shaft and having limited oscillatory movement, a suction fan mechanism power driven and connected with said discharge conduit having an outlet pipe, a disk on the shaft of the fan carrying an eccentric pin, an angle lever having a slotted arm accommodating said pin, and a link connected with the other arm of the angle lever and pivotally connected with the screen for oscillating the same.

In testimony whereof I affix my signature.

WALTER E. FULLER.
